UNITED STATES PATENT OFFICE.

MORTON G. BUNNELL, OF CHICAGO, ILLINOIS, ASSIGNOR TO FREDERICK C. AUSTIN, OF CHICAGO, ILLINOIS.

ROLLING WINDOW-SCREEN.

1,217,561.

Specification of Letters Patent. Patented Feb. 27, 1917.

Application filed July 8, 1911, Serial No. 637,542. Renewed August 19, 1916. Serial No. 115,919.

To all whom it may concern:

Be it known that I, MORTON G. BUNNELL, a citizen of the United States of America, and resident of Chicago, Cook county, Illinois, have invented a certain new and useful Improvement in Rolling Window-Screens, of which the following is a specification.

My invention relates to automatic window screens of that kind in which a flexible screen is carried on a roll and attached to the sash, whereby the opening and closing of the sash operates the screen, the latter covering the window space when the sash is open, and being wound on the roll and concealed when the sash is closed, thus obviating the necessity of having the screen across the window at all times, and making it possible to bring the screen into use by simply opening the sash.

The object of my invention is to provide an improved construction and arrangement whereby an automatic screen of this general character may be readily attached to any window without changing the construction thereof, and whereby the upper edge of the screen may be readily attached to the lower edge of the sash, and whereby the side edges of the screen are effectively guided and held against displacement, as will hereinafter more fully appear.

To these and other useful ends, my invention consists in matters hereinafter set forth and claimed.

In the accompanying drawings—

Figure 1 is a perspective of a window with the lower sash open, showing the same window with a rolling screen embodying the principles of my invention.

Fig. 2 is an enlarged fragmentary perspective view of a portion of the said screen, and of adjacent portions of the window, showing one of the guides for the side edges of the screen.

Fig. 3 is a fragmentary view of a portion of one of the sides of the screen, showing the flexible steel strip, or selvage, with which the screen is provided to keep it from being pulled out of the guide.

As thus illustrated, the window may have a frame A of any suitable or ordinary construction, no special construction being required. The screen B is of flexible wire cloth, and is provided at its upper edge with a metal reinforcing strip b having holes b' that removably engage the headed studs b²

on the sash C. The said screen has its lower portion secured to a roll D upon which it is rolled when the sash is lowered, said roll being concealed in a casing or sheet metal housing E that rests upon the window-sill a. It will be understood that the ends of the housing are provided with bearings, like those of a curtain roll, for the ends of the roll D, whereby the latter may rotate when the sash is opened and closed. As shown, said casing or housing E has its ends provided with ears e' by which it is secured to the sides of the window frame. The ends of the roll D are provided with springs d for rolling up the screen, and with provisions like those of an ordinary curtain roll, whereby the screen B is operated like an ordinary window curtain—that is to say, will stay in any position. The screen works in a slot e² in the upper corner of the casing or housing E, and the side strips b³ of the screen travel in guides F that are easily secured to the frame of any window.

Thus by embodying the screen in the form of an attachment, it is possible not only to adjust it in any window without reconstructing the frame thereof, and without building the window especially therefor, as was previously the case with automatic screens of this general character, but also to use the screen in conjunction with window ventilators of the kind which are inserted in the window below the sash.

It will be seen that the wide steel strips b³ (Fig. 3) prevent the screen from falling out of the guides F, it being understood that these guides are made to fit closely upon the said strips, whereby the latter are prevented from flexing, and as they are so wide that they cannot bend edgewise, it follows that pressure on the surface of the screen will not pull the side edges thereof out of said guides.

I do not limit myself to the exact construction shown and described.

What I claim as my invention is:

1. A rolling screen having its side edges reinforced by flat strips of flexible sheet metal, and guides for said strips, each strip being of a width to prevent edgewise flexibility thereof, and said guides depending on the edgewise stiffness of said strips to hold the edges of the screen against displacement when the window is open.

2. A rolling screen having its side edges

- reinforced by flat strips of flexible sheet metal, and guides for said strips, each strip being of a width to prevent edgewise flexibility thereof, and said guides depending on the edgewise stiffness of said strips to hold the edges of the screen against displacement when the window is open, each guide engaging the opposite surfaces of the strip to prevent flexing of the latter.
- 10 3. A rolling screen having its side edges reinforced by flat strips of flexible sheet metal, and guides for said strips, each strip being of a width to prevent edgewise flexi-

bility thereof, and said guides depending on the edgewise stiffness of said strips to hold 15 the edges of the screen against displacement when the window is open, and an attaching strip for the upper edge of said screen, the ends of said attaching strip being disposed in said guides.

Signed by me at Chicago, Illinois, this 30th day of June, 1911.

MORTON G. BUNNELL.
